UNITED STATES PATENT OFFICE.

JAMES M. SPENCER, OF OAKLEY, MICHIGAN, ASSIGNOR TO EDWARD C. EWEN, OF SAGINAW, MICHIGAN.

COMBINED DOOR STOP AND HOLDER.

No. 921,020.

Specification of Letters Patent.

Patented May 11, 1909.

Application filed August 21, 1908. Serial No. 449,689.

To all whom it may concern:

Be it known that I, JAMES M. SPENCER, a citizen of the United States, residing at Oakley, in the county of Saginaw and State of Michigan, have invented a new and useful Combined Door Stop and Holder, of which the following is a specification.

This invention relates to combined door stops and holders.

10 The objects of the invention are, the provision in a merchantable form, of a device of the above mentioned class which shall be inexpensive in construction, facile in operation and devoid of complicated parts; the 15 provision of a device which shall combine in a novel manner, means for stopping a door by mural impingement, with means for holding a door by contact with the floor.

With these objects in view, together with 20 others which will reveal to those skilled in the art, the invention consists in the novel construction and arrangement of parts hereinafter described, delineated in the accompanying drawings and particularly pointed 25 out in the appended claims, it being understood that various changes in the form, proportions, size and minor details of the structure may be made without departing from the spirit or sacrificing any of the advantages of the invention.

Similar numerals of reference are employed to indicate corresponding parts throughout the several figures of the drawings.

In the accompanying drawings, Figure 1, 35 shows in perspective my invention attached to a door, and operative to act as a door holder; Fig. 2 is a vertical longitudinal section; Fig. 2 is a horizontal section.

In carrying out my invention, I provide a 40 base plate 1, adapted to be fastened to a door; the base plate 1 may be provided with openings adapted to receive ordinary screws 2 as shown. Attached to the base-plate 1, and normally disposed thereto, is the stand- 45 ard 3, which may be formed integral with the plate 1, by a flexing of the said plate, or otherwise. The buffer 4 may be of any shape or size; I have shown it in the ordinary spherico-conical form, terminating out- 50 wardly in the resilient tip 5. The buffer 4 is slotted as shown by the numeral 6, and within the slot thus formed, is mounted the terminal of the standard 3. The base of the buffer 4 is provided with alined openings 55 adapted to register with an opening in the

outer end of the standard 3, and through these openings is passed the pintle 7, a pivotal connection being thus formed, permitting the outer end of the buffer 4 to move through an arc limited as hereinafter described.

Mounted upon the inner end of the buffer 4 preferably by the screws 13, is the foot lever 9, having a slot 8 in registration with the slot 6 in the buffer 4. The length of the slot 6 is such that when the buffer 4 is turned downward into engagement with the floor 14, as shown in Figs. 1 and 2, the foot lever 9 will clear the outer end of the standard 3; and when the buffer 4 is turned upward, the upper end of the slot 8 will come into contact with the upper edge of the standard 3, as shown in Fig. 2, limiting the upward movement of the buffer 4 upon the pintle 7, to a position normal to the base plate 1.

I further provide the oppositely disposed springs 10, shown in the drawings in helical form, having their outer ends 11 attached to the outer end of the buffer 4, their inner ends 12 attached to the base plate 1. The ends 12 are attached to the base-plate 1 at points above the pivotal connection between the buffer 4 and the standard 3, and their effect is, therefore, to pull the outer end of the buffer 4 upward when the points of attachment for the ends 11 have passed, in their upward movement, the plane occupied by the points of attachment for the ends 12 and the center of the pintle 7. This upward movement of the outer end of the buffer 4 under the tension of the springs 10, is limited by the contact between the end of the slot 8 and the upper edge of the standard 3, as hereinbefore explained. When the outer end of the buffer 4 is moved downward until the points of attachment for the ends 11 have passed in their downward movement, the plane occupied by the points of attachment for the ends 12 and the center of the pintle 7, the springs 10 will tend to pull the outer end of the buffer 4 downward, and the said buffer will then be held yieldingly in a position, substantially parallel to the base-plate 1, and downwardly inclined.

The buffer 4 stands normally at right angles to the plane of the base-plate 1 and in this position it is operative to protect the wall and the door from injuries resulting from their contact with each other when the door is swung open forcibly. When it is de- 105 110

sired to hold the door intermediate to extreme positions, pedal pressure may be applied to the foot-lever 9, whereupon the buffer 4 will be turned downward, bringing the tip 5 into contact with the floor. Reverse pressure will swing tip 5 free from the floor and place the device in a position operative to exercise its function as a door stop. By the construction herein described and shown in the accompanying drawings, it will be seen that when my invention is in use as a door-holder, the tip 5 is held yieldingly against the floor, thus obviating the possibility of tearing a carpet or marring a polished floor surface. When however, the device is used as a door stop, the buffer 4 is held rigidly in a position at right angles to the base-plate 1, the tip 5 contacting with the base-board when the door is swung back.

20 I am aware that it is not new to provide a door stop which may be turned downward to serve as a door-holder, and I make no effort to claim the combination broadly.

What I do claim as novel, is;

25 1. In a device of the class described, a base-plate adapted to receive door-engaging means; a standard attached to the base plate and normally disposed thereto; a buffer pivotally mounted upon the standard, the said buffer having a slot in its inner end adapted to receive the terminal of the standard; mounted upon the inner end of the buffer, a

foot-lever having a slot in registration with the slot in the buffer, the upper end of the slot in the foot-lever adapted to contact with the upper edge of the standard when the buffer is in a position normal to the base-plate; resilient means adapted to hold the upper end of the slot in the foot-lever in contact with the upper edge of the standard, and to hold yieldingly the buffer substantially parallel to the base plate, and downwardly inclined, in successive positions of the buffer.

2. In a device of the class described, a base-plate adapted to receive door-engaging means; a standard attached to the base plate and normally disposed thereto; a buffer pivotally mounted upon the standard; oppositely disposed springs having their outer ends attached to the outer end of the buffer, their inner ends attached to the base plate at points above the pivotal connection between the buffer and the standard; means for holding the buffer rigidly against the tension of the springs, in a position normal to the base-plate.

In testimony that I claim the foregoing as my own, I have hereto affixed my signature in the presence of two witnesses.
